UNITED STATES PATENT OFFICE.

MATT BURNS, OF TWIN VALLEY, MINNESOTA.

WASHING-MACHINE.

1,206,299.

Specification of Letters Patent. Patented Nov. 28, 1916.

Application filed September 5, 1916. Serial No. 118,504.

To all whom it may concern:

Be it known that I, MATT BURNS, a citizen of the United States, residing at Twin Valley, in the county of Norman and State of Minnesota, have invented certain new and useful Improvements in Washing-Machines, of which the following is a specification, reference being had to the accompanying drawings.

10 This invention relates to certain improvements in washing machines and has relation more particularly to a device of this general character including a rocking body; and it is an object of the invention to provide novel 15 and improved means whereby the requisite movement may be imparted to the body.

The invention also has for an object to provide a device of this general character having novel and improved means whereby 20 the requisite movement may be imparted to the body either manually or mechanically.

The invention consists in the details of construction and in the combination and arrangement of the several parts of my improved 25 washing machine whereby certain important advantages are attained and the device is rendered simpler, less expensive and otherwise more convenient and advantageous for use, all as will be hereinafter 30 more fully set forth.

The novel features of the invention will hereinafter be definitely claimed.

In order that my invention may be the better understood, I will now proceed to 35 describe the same with reference to the accompanying drawings, wherein—

Figure 1 is a view in elevation illustrating a churn constructed in accordance with an embodiment of my invention; Fig. 2 is a 40 fragmentary view in vertical section illustrating certain details of the invention as herein embodied; and Fig. 3 is a fragmentary sectional view taken substantially on the line 3—3 of Fig. 1.

45 As disclosed in the accompanying drawings, F denotes a frame of predetermined configuration and dimensions and including substantially parallel horizontal beams 1 which afford a mounting for the trunnions 2 carried by the ends or heads 3 of the working body B substantially cylindrical in form and preferably of a configuration of the general type of barrel.

Carried by the side wall 4 of the body B 50 is a plurality of series of pins 5 disposed

longitudinally of the body and preferably formed of wood. The outer ends of each of the pins 5 are rounded while the opposite ends thereof are threaded so that the same may be detachably engaged with the wall 4 60 of the body B.

One of the trunnions 2 extends a sufficient distance outwardly of the coating beam 1 as to have affixed thereto the crank 6 having its outer or free end portion provided with a wrist pin 7 with which is operatively engaged a pitman 8 also operatively engaged with the driven wheel 9. As herein disclosed the wheel 9 is operatively engaged with a gear 10 of less diameter than the 70 wheel and which is adapted to be driven from a suitable source of power as indicated through the medium of the belt 11.

It will be perceived that upon rotation of the wheel 9 the body B will be caused to 75 rock so that requisite agitation may be imparted to the articles within the body B to thoroughly cleanse said articles. The body B is provided with the door 12 of any conventional type to afford means whereby the 80 cleansing fluid and articles may be readily placed within the body B.

In order to permit the body B to be rocked manually, I pivotally engage with the frame F the upstanding lever 14 with 85 which is operatively engaged a second pitman 15 which is also operatively engaged with the crank 6. It is also preferred that the pitmen 8 and 15 be detachably engaged with the crank 6 or more particularly the 90 wrist pin 7 thereof so that when the power means is employed for operating the body, the pitman 15 may be disengaged and vice versa.

95 Imposed above each of the beams 1 is a strip 16 and between said strip 16 and the beam 1 are interposed the expandable members 17 herein disclosed as conventional coil springs of requisite tension. Carried by each of the heads 3 is an outstanding finger or stop 18 which contacts with the adjacent strip 16 whereby a rebound action is afforded to facilitate the rocking action of the body B.

Extending inwardly from the frame F at 105 the top thereof on a predetermined incline is a drain board D, and said frame F is adapted to have secured thereto adjacent the upper end of the board D a conventional 110 wringer so that the water forced from the

articles passing through the wringer may be carried by the drain board and discharged within the body B, it being understood that during the wringing operation 5 the body B will be adjusted so as to have the door 12 positioned below the lower or discharge end of the board D.

From the foregoing description, it is thought to be obvious that a washing machine constructed in accordance with my invention is of an extremely simple and comparatively inexpensive nature and is particularly well adapted for use by reason of the convenience and facility with which it 10 may be assembled, and it will also be obvious that my invention is susceptible of some change and modification without material departure from the principles and spirit thereof and for this reason I do not wish 15 to be understood as limiting myself to the precise arrangement and formation of the several parts herein shown in carrying out 20

my invention in practice, except as herein-after claimed.

I claim:

A washing machine comprising spaced beams, a body interposed between the beams and rotatably supported thereby, means for rocking the body, an elongated strip 25 acting with one of the beams, expansible means interposed between and secured to the strip and beam and holding said strip in suspension, said expansible means being positioned at opposite sides of the axial center of the body, and a stop carried by an end of the body and arranged for contact with the strip at the limit of movement of the body in either direction.

In testimony whereof I hereunto affix my signature in the presence of two witnesses. 40

MATT BURNS.

Witnesses:

A. J. VANGNESS,
A. S. HAIN.
